UNITED STATES PATENT OFFICE.

EDGAR F. PALMER AND ORION G. HARDIN, OF LOUISVILLE, KENTUCKY.

COMBINATION SOFA-BED AND WARDROBE-COUCH.

SPECIFICATION forming part of Letters Patent No. 678,026, dated July 9, 1901.

Application filed December 7, 1899. Serial No. 739,482. (No model.)

To all whom it may concern:

Be it known that we, EDGAR F. PALMER and ORION G. HARDIN, citizens of the United States, residing at Louisville, in the county of Jefferson and State of Kentucky, have invented certain new and useful Improvements in a Combination Sofa-Bed and Wardrobe-Couch; and we do declare the following to be a full, clear, and exact description of the invention, such as will enable others skilled in the art to which it appertains to make and use the same, reference being had to the accompanying drawings, and to the letters of reference marked thereon, which form a part of this specification.

Our invention relates to improvements in sofas or couches so constructed as to be convertible into beds for sleeping in; and the objects of our improvements are to make an article of furniture which will serve as a comfortable sofa and can be easily and readily converted into a strong and comfortable bed and be as readily changed back into a sofa and provided with a receptacle for bed or other clothing. We attain these objects by the means illustrated in the accompanying drawings, in which for better understanding of its construction the framework of our device is shown without the upholstering.

Figure 1 is a front elevation of the device, showing it closed for use as a sofa and with one end of the box broken away to show interior elements thereof. Fig. 2 is an end view of the same with the end pieces of the back and box removed. Fig. 3 is a view similar to Fig. 2, except that it shows a position assumed by the parts during the conversion of the device from a sofa into a bed, or vice versa. Fig. 4 is a view similar to Fig. 3, showing the device converted into a bed. Fig. 5 is a detail view showing the relative position of a leg D and its lever d when the leg is drawn into the back.

Similar letters refer to similar parts throughout the several drawings.

The box-like base A, seat B, back C, and legs D constitute the frame of the device. Within the box A, near each end, is placed a transverse piece A', parallel with the ends of the box, so as to form chambers between said transverse pieces and the ends of the box, and within said chambers are pivoted

eccentrically rods or bars a, having their shorter arms toward the rear of the box and their longer arms toward the front thereof. 55

The back C is hinged at its lower side to the seat B, as shown at C', and said seat is hinged at its lower end to the upper rear end of the box A, as shown at B². The bottom of said seat is preferably formed by a series of slats B', (shown in dotted lines in Figs. 2 and 3,) and its ends, which constitute sofa-arms, are each formed of two parallel pieces of plank b, having a top plank b* over them (shown in dotted lines in Fig. 1) and fastened 60 to an ornamental face b** at each end, thus forming chambers in said ends. Within each of said chambers is pivoted, near its front end, a weighted lever b', which projects rearwardly through the back-piece b** and has its 65 rear end formed to provide a hook which engages a suitable catch, as c, located in the frame of the back, so as thereby to hold said back perpendicular to the seat when the device is not converted into bed form. Each 70 end of the back C also preferably is formed to provide a chamber, within which chambers the legs D lie and are concealed when they are not in use. These legs are attached at their upper ends to the frame of the back by 75 the hinges D*, and at their upper ends they are formed or provided with beveled heads D', which project laterally in opposite directions therefrom. The legs are preferably connected together by a rung or brace d². On 80 each side of each leg is a gooseneck-lever d, pivoted on a dowel-pin supported by the back frame near the beginning of the neck and having a nick at the end adapted to engage the head or angular projection D', formed 85 on each side of the top of the leg. The levers on each side of the leg are connected together into pairs by a weight-piece d³, extending across from one to the other from their bottom surfaces in the rear of the pivot and 90 back of the leg when folded. A cord or chain d' connects the inner end of the outer of these paired levers to the back of the box A near its top. It will be observed that the paired levers are located and operate within 95 the chambers at the ends of the back C, which chambers thus conceal and protect said levers and prevent the same from coming in contact with the clothing stored in the box.

100

A cord a' is attached at one end to the end of the long arm of each of the eccentric levers a and at the other end to the front slat of the seat, and a cord a^2 is fastened at one end to the end of each of the short arms of the levers a , and thence passes over a pulley fixed in the outer edge of the back slat of the seat near its end, and thence over a pulley attached to the frame of the back at its top and near its end, and thence over the top of the leg D , to the outer face of which it is attached at a point about one-third the length of the leg below its top end. A cord or chain a^3 , having a handle a^4 , (shown in Fig. 3 and in dotted lines in Figs. 1, 2, and 5,) extends, below the seat, from the bottom of one of the slats of which it is supported in the middle, over a pulley fixed at each end of the seat-frame immediately under the ends of the weighted levers b' and is attached to those ends.

When it is desired to convert the sofa, as shown in Fig. 1, into a bed, as shown in Fig. 4, the seat is raised to the perpendicular, throwing the back parallel to the floor. As the back is lowered the legs fall by their own weight toward a perpendicular. In raising the seat the cords or chains a' , attached to the ends of the long arms of the levers a , are tightened, raising the long arms and depressing the short arms, and thereby tightening the cords or chains a^2 , connecting the ends of the short arms with the legs D , as described, and bringing the legs perpendicular to the floor, when the nicks in the ends of the paired gooseneck-levers d engage the angular projections formed on each side of the tops of the legs D and hold them in position. (See Figs. 3 and 4.) The clothing or other furnishings for the bed can then be taken from the open box, and then the handle a^4 to the cord a^3 is pulled, which disengages the hook in the outer ends of the weighted levers b' in the ends of the seat from the catches c in the back and the seat is lowered onto the box A and the bed is formed. When it is desired to change back from the bed form to the sofa form, the bedclothes are removed, the seat raised to the perpendicular, uncovering the box A , whereupon the weighted levers b' automatically engage the catches c in the back and hold the seat elevated, the clothes are put in the box A , the seat is lowered again onto the box, bringing the back to its perpendicular position, and at the same time tightening the cord or chain d' , connecting the inner ends of the gooseneck-levers d with the back of the box, thereby disengaging the nicks in the ends of those levers from the angles at the top of the legs and allowing the legs and their connecting-rung to swing back into their chambers as the back rises.

The weight of the seat will prevent the back of the sofa from tipping backward, but if necessary a lock can be provided on the front of the box A to hold the seat down.

Having thus described our invention, what we claim as new, and desire to secure by Letters Patent of the United States, is—

1. A combined wardrobe - bed and sofa-couch, embodying a box-like base, a seat having chambered sofa-arms at its ends, said seat being pivotally attached at the lower end of its rear side to the rear side of said base, a back hinged at the lower end of its front side to said seat, pivoted legs carried by said back, horizontal levers contained and pivoted within the chambers in the sofa-arms and having hook ends extending rearwardly from said chambers, catches carried by said back to be engaged by said hook ends and thereby cause said seat and back to swing together around the pivotal connection of the seat with the base, and means actuatable to disengage said hook ends from said catches to thereby permit said back to swing upon its hinges relatively to said seat, substantially as described. 70

2. A combined wardrobe - bed and sofa-couch, embodying a box-like base, a seat pivotally attached thereto at one side, a back pivotally attached to said seat, a hook and a catch coacting to hold the seat and back together, said back having chambered ends, legs pivoted at their upper ends in said chambers and swinging therefrom into a perpendicular position when the back is lowered, pivoted levers carried by said back and arranged wholly in said chambers and engaging the pivoted ends of said legs when the latter are perpendicular, and means for detaching said levers from the legs. 90

3. A combined wardrobe - bed and sofa-couch, embodying a box-like base, a seat pivotally attached thereto at one side and having its ends constructed to provide closed chambers, a back pivotally attached to said seat and having chambered ends, a hook and a catch in contiguous chambers, for holding the seat and back together, legs pivoted at their upper ends in the chambers of the back and adapted to swing therefrom into perpendicular position when the back is lowered, pivoted levers in the chambers of said back for holding the legs in perpendicular position, means for detaching said hook from the catch, and means for detaching said levers from the legs. 105

4. A combined wardrobe - bed and sofa-couch, embodying a box-like base, a seat pivotally attached thereto at one side, a back pivotally attached to said seat, a hook and a catch coacting to hold said seat and back together, legs pivoted at their upper ends to said back and having laterally-projecting beveled heads, a pair of connected pivoted levers for each leg, having ends adapted to engage the heads of the latter, and means for disengaging said ends from said heads. 120

5. A combined wardrobe - bed and sofa-couch, embodying a box-like base, a seat pivotally attached thereto at one side, a back pivotally attached to said seat, a hook and a 130

catch coacting to hold the seat and back together, legs pivoted to said back, levers eccentrically pivoted in said base, means connecting the longer arms of said levers with 5 said seat, and means connecting the shorter arms of said levers with said legs.

6. A combined wardrobe - bed and sofa-couch, embodying a box-like base, a seat pivotally attached thereto at one side and having chambered ends, a back pivotally attached to said seat and having chambered ends, a lever pivoted between its ends in each of the chambers in the ends of said seat and having its rear end projected therefrom and of hook 15 form, a catch in the chamber of said back to be engaged by said hook end, means attached to the front ends of said levers for disengaging the rear ends thereof from said catches, legs pivoted at their upper ends in chambers 20 of said back and adapted to swing from said chambers into perpendicular position with respect to said back, and means for holding said legs in perpendicular position when the back is lowered and for swinging the same

into said chambers while the back is being 25 elevated.

7. A combination sofa-bed, wardrobe and couch, having a box-base, a seat hinged thereto, a back hinged to the rear of the seat, and legs hinged to said back, combined with levers, pivoted in said base and each connected at one end with the seat and at its other end with a leg, weighted levers mounted in the seat, catches secured to the back in position to be engaged by said weighted levers, levers 30 arranged to engage the legs, connections between said levers and base, and means connecting the weighted levers together and operated to disengage the same from said catches, substantially as described and for 35 the purposes set forth.

In testimony whereof we affix our signatures in presence of two witnesses.
